DERIVATIVES OF PENICILLIN AMIDES
 Thomas A. Seto, Groton, Conn., assignor to Chas. Pfizer &
 Co., Inc., New York, N.Y., a corporation of Delaware
 No Drawing. Filed Dec. 6, 1961, Ser. No. 157,334
 14 Claims. (Cl. 260—239.1)

This invention relates to new antibiotic compounds and, more particularly, to novel penicillin derivatives which are active against the antibiotic resistant Staphylococci.

The term "penicillin" describes a group of acyl derivatives of 6-amino-penicillanic acid which differ only in the nature of the R group and possess the general Formula I wherein the acyl moiety is derived from a carboxylic acid or functional derivative thereof such as an acyl chloride, anhydride or amide.

The properties, particularly the antibiotic properties, of a given penicillin are determined to a large extent by the R group. The best known and most widely used penicillins, benzylpenicillin, phenoxymethylpenicillin, and, more recently, α -phenoxyethylpenicillin, wherein R represents the benzyl-, phenoxy-methyl- and α -phenoxyethyl-radicals, while highly antagonistic toward gram positive microorganisms, are ineffective against the so-called antibiotic resistant strains of bacteria, that is, the penicillin or antibiotic resistant Staphylococci, and are readily destroyed by penicillinase. Antibiotic resistant bacteria, Staphylococci in particular, are becoming the most important cause of severe infections and deaths in hospitals today. Therefore, drugs which will combat the continuing rise in Staphylococci incidence and fatality are of immeasurable value to the medical profession.

It has been unexpectedly found that amide derivatives of α -alkoxyalkyl- and α -alkylmercaptoalkylpenicillins possess surprising activity against the antibiotic resistant Staphylococci both in vitro and in vivo. The novel compounds of the present invention have Formula II:

wherein R_1 is selected from the group consisting of straight-chain and branched-chain alkyl containing up to and including six carbon atoms; R_2 is selected from the group consisting of R_1 and $\text{R}_4-\text{X}-\text{R}_3$ —wherein R_3 is selected from the group consisting of straight- and branched-chain alkylene containing two to three carbon atoms, inclusive; R_4 is selected from the group consisting of straight- and branched-chain alkyl containing up to and including 4 carbon atoms; and X is selected from the group consisting of oxygen and sulfur. R_1 and R_4 may be alike or different.

These novel compounds can exist in epimeric "D" and "L" forms derived respectively from the D- and L-precursor acids. It will be convenient to refer to these epimers as the D- and L-epimers. When a DL-precursor acid is used, a mixture of the D- and L-epimers is produced. Therefore, included within the purview of this invention are the D- and the L-epimers and mixtures thereof of the compounds of Formula II above, each of which exhibits substantial therapeutic activity.

In addition to their unexpected and significant activity against the antibiotic resistant Staphylococci, the novel products of this invention are resistant to destruction by

2

penicillinase, the penicillin destroying enzyme elaborated by many microorganisms, and are also antagonistic toward other Gram-positive micro-organisms.

The in vitro and especially the in vivo antagonism of these valuable products toward the resistant Staphylococci is indeed surprising and unexpected since the acid forms of these novel penicillins, the compounds of Formula II wherein the carboxamide group is replaced by a carboxy group or an alkali metal salt thereof, possess little or no activity against the resistant Staphylococci. The in vivo activity is all the more surprising in view of the absence of in vivo activity in benzylpenicillin amide. Furthermore, chemical modification of the penicillin molecule has, up until the discovery of the present class of compounds, resulted in significant activity against the resistant Staphylococci only through modification of the acyl side chain. Previous attempts to impart new antibiotic properties to the penicillins (Cooper, J. Am. Chem. Soc. 70, 3966 (1948) and Holysz et al., J. Am. Chem. Soc. 72, 4760 (1950)) via amide formation have resulted in conflicting data as to the in vivo efficacy of such amides. Repetition of the prior art experiments has confirmed the findings of Holysz et al. (loc. cit) that amide formation of penicillins e.g. benzylpenicillin, imparts no in vivo activity to the penicillin. It has been found that conversion of penicillins to their amide derivatives does not, in general, impart or enhance in vivo activity against the resistant strains of Staphylococci. Indeed, enhancement of such activity by amide formation appears to be the exception rather than the rule. The penicillin amides are generally somewhat less active against the Gram-positive microorganisms than are the parent acids.

The in vitro antimicrobial activity of a variety of α -alkoxyalkylpenicillin amides and α -alkylmercaptoalkylpenicillin amides against the antibiotic resistant strains of *Staphylococcus aureus* 376, 400 and K₃ are listed in Table I along with similar data for the amides of benzylpenicillin and phenoxymethylpenicillin. The minimal inhibitory concentrations (MIC) are reported in terms of mcg./ml.

TABLE I
 [In Vitro Data (mcg./ml.)]

45	Penicillin Amide	Antibiotic Resistant <i>S. aureus</i> Strains		
		376	400	K3
50	α -Methoxy-n-propyl	12.5	3.12	
	α -Isobutoxy-n-propyl	25	6.25	1.56
	α -Isoamyoxy-n-propyl	6.25	0.39	3.12
	α -n-Amyloxy-n-propyl	1.56	0.78	25
	α -Methoxyamyl		5	
	α -Isoamyoxyethyl	10	10	
	α -n-Amyloxyethyl	5	2.5	
	α -Isobutoxyethyl	5	1.25	
	α -n-Propylmercaptoethyl	25	3.12	1.56
	α -Methylmercaptoethyl	50	12.5	12.5
	α -Isopropylmercaptoethyl	100	6.25	6.25
	α -Butyloxyethyl	25	25	
	Phenoxymethyl	3.12	6.25	
	Benzyl	3.12	6.25	
	α -Methylmercapto-n-amyl		1.56	
	α -Methylmercaptoisobutyl		3.12	
	α -Methylmercapto-n-butyl		25	
60	α -n-Butylmercaptoethyl		12.5	

The remarkable and unexpected therapeutic value of the novel products of this invention is brought out by a comparison of the in vivo activity of these products with that of phenoxymethylpenicillin amide against the penicillin resistant *S. aureus* 400 infection in mice. The PD₅₀ values (the protective dose 50) that is, the dosage which will bring about 50% survival of the test animals, for several α -alkoxyalkyl- and α -alkylmercaptoalkylpenicillin amides of the present invention are given in Table II in

terms of mg./kg. and compared with PD_{50} values obtained with the amide of phenoxyethyl- penicillin.

TABLE II
[PD_{50} Values (mg./kg.)]

Penicillin Amide	<i>S. aureus</i> 400		10
	Oral	Parenteral	
α -Methoxy-n-propyl	18	12.5	
α -Isoamylxy-n-propyl		50	
α -Isobutoxyethyl	100	60	
α -Methoxyamyl	50	33	
α -Methylmercaptopropyl	70	30	
α -Methylmercaptobutyl	100	>50	
α -Methylmercaptoisobutyl	76	70	
Phenoxyethyl	>400	>200	15

The valuable products of this invention are remarkably effective in treating a number of infections, particularly those caused by antibiotic resistant *Staphylococci*, in poultry and animals including man. For this purpose the pure material or mixtures thereof with other antibiotics can be employed. In order to do this for administration to man and animals, a non-toxic carrier, that is, a carrier which is non-toxic when administered in a quantity sufficient to provide the required dosage of the desired penicillin is selected. This may be either a pharmaceutical carrier, either a liquid or a solid, such as water, aqueous ethanol, syrup, isotonic saline or glucose, starch, lactose, calcium phosphate or animal feed stuff. Either oral or parenteral administration is satisfactory. However, because of ease of administration the oral route is preferred.

The novel and valuable products of this invention are prepared by amidation of a simple or mixed anhydride of the appropriate penicillin with ammonia in a non-aqueous solvent. The reaction is conducted in a reaction-inert solvent such as chloroform, dimethylacetamide, tetrahydrofuran, methylisobutylketone and acetone, at a temperature of from about -10° C. to about 50° C. Alternatively, an ammonium salt, such as diammmonium phosphate in an aqueous alkaline solution is used.

The penicillin mixed anhydrides are readily prepared by treating an alkali metal salt, e.g. the sodium or potassium salt, of the desired penicillin with an acid chloride of the second acid component in a suitable anhydrous solvent, such as chloroform, at from about -10° C. to about 50° C. Alternatively, they are prepared by the reaction of the penicillin acid with a carbodiimide, preferably an aliphatic or alicyclic carbodiimide, e.g. 1,3-dicyclohexylcarbodiimide according to the well known procedures.

The simple penicillin anhydrides are prepared by reacting the triethylammonium salt of the desired penicillin with thionyl chloride.

It should be noted that, in preparing the penicillin amides from an alkali metal salt or triethylammonium salt, it is not necessary to isolate the intermediate products, e.g. the penicillin acids and anhydrides, as is demonstrated more fully below. It is far more convenient from a practical standpoint to use the intermediate in the form of the solution in which it is prepared.

The novel penicillin precursors, that is, the free acid form and alkali metal salts thereof of the compounds of Formula II, are prepared from 6-aminopenicillanic acid by any of the several known methods for introducing an acyl substituent into a primary amine.

They can, for example, be prepared by the acylation of 6-aminopenicillanic acid with the appropriate acid chloride, acid bromide, simple anhydride or mixed anhydride. Alternately, they can be prepared by the reaction of 6-aminopenicillanic acid with the appropriate acid precursor in the presence of a condensing agent, e.g., a carbodiimide, such as 1,3-dicyclohexylcarbodiimide.

They can also be prepared by the method of Sheehan et al., Journal of the American Chemical Society, 81, 3089 (1959) which utilizes D-penicillamine and t-butyl phthal-

imidomalonaldehyde as starting materials for a series of reactions. Substitution of the phenoxyacetyl chloride utilized by Sheehan et al., by, for example,

in the reaction sequence produces the potassium salt of the desired penicillin.

The 6-aminopenicillanic acid can be used in the form of the pure material dissolved or suspended in the solvent of choice, e.g., water, aqueous acetone, or in the form of a fermentation liquor or concentrate thereof.

It is preferred to utilize the reaction of 6-aminopenicillanic acid with the desired acid chloride in the presence of an acid acceptor at a pH of from about 3.0 to about 9.0 and a temperature of from about 0° C. to about 50° C. A neutral to moderately alkaline pH level, that is pH values of from about 6.0 to about 9.0 are favored since, under these conditions, a substantial yield of the desired product is produced.

When prepared in this manner the novel penicillins are obtained as their sodium or potassium salts. They are readily converted to the acid form by acidification with a mineral acid, such as sulfuric or hydrochloric acid, and are recovered by extraction, filtration or centrifugation of the precipitated acid.

The preparation of the epimers or mixtures thereof of these novel products is most conveniently and preferably accomplished by reacting 6-aminopenicillanic acid with the appropriate modification, that is, with the DL- or with the D- or the L-component of the precursor acid or acid chloride. The epimeric penicillins can be separated from mixtures thereof by fractional crystallization, selective extraction, or selective precipitation of an insoluble salt of one epimer in the presence of the other. The amide derivatives of a given D- or L-epimer, or mixture thereof are prepared as described above.

The L-epimers are somewhat more active than the D-epimers. Mixtures of the two epimers of a given penicillin amide appear to have activity at least equal to that expected from a summation of the individual activities.

The α -alkoxyalkanoic and α -(alkoxyalkoxy)alkanoic acid reactants and the sulfur analogs thereof are prepared by reaction of the appropriate α -bromoalkanoic acid with the proper sodium alcoholate or sodium thioalcoholate in accordance with known procedures. A preferred method of preparation utilizes the reaction of the appropriate ethyl- α -bromoalkanoate with the desired solid sodium alcoholate or thioalcoholate under anhydrous conditions at about 150° C. to about 200° C. The product is saponified to the sodium or potassium salt and the acid recovered therefrom by acidification. The acid chloride is prepared by reaction of the acid with thionyl chloride according to procedures well known in the art.

The amides of the α,α -(dialkoxy)alkyl-penicillins and the corresponding sulfur analogs, that is, the compounds of Formula II wherein the hydrogen of the α -carbon atom is replaced by an $-XR_2$ group and wherein R_1 is hydrogen as well as alkyl as defined above, also exhibit similar antagonisms toward the antibiotic resistant *Staphylococci* and Gram-positive microorganisms in general. They are, therefore, highly useful for treating infections caused by such microorganisms in poultry, animals and man. The parent penicillin precursors of these valuable products are conveniently prepared by the carbodiimide procedure described above and are converted to the amide by Procedures A or B. The necessary α,α -(dialkoxy)alkanoic acid reactants, and their sulfur analogs are prepared from the appropriate α,α -dihalo(chloro or bromo)alkanoic acid by reaction with an alkali metal salt of the alcohol or mercaptan having the desired R_2 moiety.

The substitution of ammonia by a primary or secondary amine of the formula $R'NH_2$ or $R'R''NH$ where R' and R'' are selected from the group consisting of lower alkyl, hydroxy (lower) alkyl, α -carboxy (lower) alkyl, β -carboxy (lower) alkyl, halo (lower) alkyl, alicyclic, aryl, substi-

tuted aryl, benzyl, R' and R'' when taken together represent a 5- and 6-membered ring which may contain a hetero atom, produces valuable isoiclic products having a greater or lesser solubility in water than the unsubstituted amide.

Primary and secondary amines representative of the above compounds are methylamine, dimethylamine, butylamine, cyclohexylamine, (2-hydroxyethyl)amine, di-(2-hydroxyethyl)amine, glycine, β -alanine, piperazine, piperidine, 2-chloroethylamine, aniline, benzylamine, and cycloserine.

The following examples are provided to further illustrate in detail methods for the procedure of the present invention. They are, however, not to be construed as limiting the invention in any way.

Example 1

To a well stirred solution of 16 grams of 6-aminopenicillanic acid, 200 ml. of 3% sodium bicarbonate, 100 ml. of acetone and 2.5 ml. of 50% sodium hydroxide, a solution of 10 grams of DL- α -methoxy-n-butyryl chloride in 100 ml. of acetone is gradually added over a one hour period at 0° C. The pH is maintained at 7.5 by the addition of sodium hydroxide. The mixture is stirred at room temperature for a half hour following completion of addition. 100 ml. of water is then added and the solution extracted with an equal volume of ether. The ether phase is discarded, the aqueous phase adjusted to pH 2.5 with phosphoric acid then extracted twice with 150 ml. of methylisobutylketone. The combined methylisobutylketone extracts are then extracted with 100 ml. of water and divided into two equal volumes, A and B. Volume A is dried over anhydrous sodium sulfate and the resulting dry solution of DL- α -methoxy-n-propylpenicillin used in Procedure A below. To volume B 60 ml. of water is added and the pH adjusted to 6.5 by the addition of 5 N potassium hydroxide. The aqueous phase is separated and freeze-dried to give a mixture of the D- and L-epimers of the potassium salt of α -methoxy-n-propylpenicillin as a powder. The product is used in procedure B below.

PROCEDURE A

0.032 mole of triethylamine in 15 ml. of acetone is added to volume A at 0°-5° C. and the mixture stirred for 10 minutes. A solution of 0.032 mole of ethylchlorocarbonate in 30 ml. of dry acetone is added and, after 10 minutes agitation, the mixture cooled to -50° C. A solution of 0.03 mole of diammonium phosphate in 15 ml. of 3% sodium bicarbonate, chilled to -5° C., is then slowly added to the mixed anhydride. The mixture is allowed to reach room temperature and is then stirred for 20 minutes.

The mixture of the amides of D- and L- α -methoxy-n-propylpenicillin is isolated by extraction with 2 x 75 ml. portions of methylisobutylketone and the combined extracts washed with 2 x $\frac{1}{4}$ volumes of 1% sodium bicarbonate solution and $\frac{1}{4}$ volume of water. The solution is dried over anhydrous sodium sulfate then evaporated in vacuo to a heavy syrup. The product is precipitated by the addition of 75 ml. of n-hexane, the solid filtered, taken up in chloroform and reprecipitated as before by the addition of n-hexane. It is recovered by filtration and dried.

PROCEDURE B

A solution of 0.03 mole of the potassium salts of D- and L- α -methoxy-n-propylpenicillin (prepared above) in 50 ml. of water is adjusted to pH 1.5 with dilute hydrochloric acid and extracted into 3 x 50 ml. volumes of ether. The combined ether extracts are then dried over anhydrous sodium sulfate and treated with an equimolar quantity of 1,3-dicyclohexyl carbodiimide dissolved in 100 ml. of ether. After 30 minutes at room temperature, a solution of 0.03 mole of diammonium phosphate (pH 7-8) is added and the mixture stirred for two hours at room temperature and pH 7-8 and filtered. The filtrate is extracted with 2 x $\frac{1}{3}$ volumes of chloroform. The combined extracts are washed with dilute (1%) sodium bicarbonate and water, then dried with anhydrous

sodium sulfate, evaporated to a heavy syrup, and the amides precipitated by the addition of n-hexane.

The product is identical to that obtained in Procedure I-A.

PROCEDURE C

Procedure A above is repeated but with replacement of the sodium bicarbonate-diammonium phosphate solution by a saturated solution of ammonia in isopropanol (a 10% excess of ammonia is used). The product, isolated according to the method of Procedure A, is identical to that obtained in Procedure A.

Example II

The procedure of Example I is repeated employing the D- and L-epimers of α -ethoxy-n-butyrylchloride in place of α -methoxy-n-butyrylchloride. The α -ethoxy-n-propylpenicillin thus obtained is then reacted according to Procedure A to give the amides of the D- and L-epimers of α -ethoxy-n-propylpenicillin.

Example III

A number of α -alkoxyalkyl- and α -alkylmercaptoalkyl penicillin amides are prepared according to Procedures A and B as mixtures of the D- and L-epimers from the corresponding penicillin prepared by the method of Example I. Such compounds are listed below together with the procedure employed for conversion of the penicillin to the amide.

Penicillin:

		Procedure
30	α -Methoxyethyl	A
	α -Methoxy- β -methylpropyl	A
	α -Ethoxyethyl	A
	α -Isobutoxyethyl	A
35	α -Methoxy-n-butyl	B
	α -Ethoxy-n-butyl	B
	α -(n-Butoxy)-n-propyl	A
	α -Methoxy-n-pentyl	A
	α -(n-Propoxy)-n-propyl	A
	α -Isopropoxy-n-propyl	A
	α -Methoxy- β , β -dimethylpropyl	A
	α -Ethoxy-n-pentyl	A
	α -Ethoxy-n-heptyl	C
	α -Isobutoxy-n-propyl	A
	α -Ethoxy-n-hexyl	A
	α -(t-Butoxy)-n-propyl	A
	α -n-Hexoxy-n-heptyl	A
	α -Methoxy-n-methylbutyl	B
	α -Isopropoxy- β -methylpropyl	A
	α -n-Amyloxy-n-hexyl	A
	α -Methylmercapto-n-propyl	A
	α -Ethylmercapto-n-propyl	A
	α -Methylmercapto- β -methylpropyl	A
	α -Isopropylmercapto-n-propyl	A
	α -n-Amyloxyethyl	C
	α -Isoamyloxyethyl	C
	α -Methoxy-n-amyl	A
	α -Hexoxy-n-propyl	A
	α -Methylmercapto-n-butyl	B
	α -Methylmercapto-n-heptyl	B
	α -Methylmercapto-n-pentyl	B
	α -n-Propylmercapto-n-heptyl	B
	α -Butylmercapto-n-propyl	A
	α -Isoamylmercapto-n-propyl	B
	α -Ethylmercaptoethyl	A
60	α -Isobutylmercaptoethyl	A

Example IV

α -(Methoxyethoxy)-ethylpenicillin is prepared by the method of Example I and is converted to the amide by Procedure B.

Additional penicillin amides of Formula II wherein R_2 is R_4-X-R_3 are prepared using suitable α -(alkoxyalkoxy)alkanoic acids and α -(alkylmercaptoalkylmercapto)-alkanoic acids as starting materials in place of α -(methoxyethoxy)propionic acid.

Penicillin

α -(Ethoxycethoxy)ethyl
 α -(n-Propoxyethoxy)ethyl
 α -(Butoxyethoxy)ethyl
 α -(n-Propoxy-n-propoxy)ethyl
 α -(Methoxyethoxy)-n-propyl
 α -(Methoxyethoxy)-n-butyl
 α -(Methoxyethoxy)-n-pentyl
 α -(Methoxyethoxy)- β -methylpropyl
 α -(Methoxy-n-propoxy)ethyl
 α -(Isopropoxyethoxy)ethyl
 α -(Methylmercaptoethylmercapto)ethyl
 α -(Ethylmercaptoethylmercapto)-n-propyl
 α -(n-Propylmercapto-n-propylmercapto)-n-butyl
 α -(n-Butylmercaptoethylmercapto)ethyl
 α -(Methoxyisopropoxy)ethyl
 α -(Methylmercaptoisopropylmercapto)ethyl
 α -(n-Butoxyisopropoxy)ethyl
 α -(Methoxyisopropoxy)- β -methylbutyl
 α -(Methoxyisopropoxy)ethyl
 α -(Ethoxyisopropoxy)ethyl
 α -(Ethoxyisopropoxy)-n-propyl
 α -(Methylmercaptoisopropylmercapto)ethyl
 α -(Ethoxyethoxy)-n-heptyl
 α -(Methoxyethoxy)-n-hexyl
 α -(Methylmercaptomethylmercapto)-n-hexyl
 α -(Ethylmercaptoethylmercapto)-n-heptyl

It should be noted that in those preparations wherein R_3 represents the isopropylene moiety, a mixture of two products is obtained. In these products the branched methyl group of the isopropylene moiety may lie on the first or second carbon of the alkylene moiety.

Example V

The procedure of Example I is reprinted employing the L-epimer of α -methoxy-n-butyryl chloride in place of the DL-epimeric mixture. The L- α -methoxy-n-propylpenicillin thus produced is converted to the amide by the method of Procedure A.

Similarly, additional epimeric amides are prepared employing the methods of Example I and Procedure A.

Penicillin amide

D- α -Methoxy-n-propyl
 L- α -Methoxy-n-butyl
 L- α -Ethoxyethyl
 D- α -Ethoxyethyl
 L- α -Methylmercapto-n-propyl
 D- α -Methylmercapto-n-propyl
 D- α -Methoxy-n-hexyl
 L- α -Methoxy-n-hexyl
 D- α -Ethylmercapto-n-heptyl
 L- α -Hexoxy-n-propyl

This application is a continuation-in-part of application Serial No. 80,524, filed January 4, 1961 and now abandoned.

What is claimed is:

1. A compound having the formula:

- 10 wherein R_1 is selected from the group consisting of straight-chain and branched-chain alkyl radicals having from 1 to 6 carbon atoms; R_2 is selected from the group consisting of R_1 and R_4-X-R_3 —wherein R_3 is selected from the group consisting of straight and branched-chain alkylene having from 2 to 3 carbon atoms; R_4 is selected from the group consisting of straight-chain and branched-chain alkyl having from 1 to 4 carbon atoms; and X is selected from the group consisting of oxygen and sulfur.

15 2. The compound represented by the formula of claim 1 wherein R_1 is alkyl containing 1 to 6 carbon atoms, R_2 is methyl and X is oxygen.

20 3. The compound represented by the formula of claim 1 wherein R_1 is alkyl containing 1 to 6 carbon atoms, R_2 is ethyl and X is oxygen.

25 4. The compound represented by the formula of claim 1 wherein R_1 is methyl, R_2 is alkyl containing 1 to 6 carbon atoms and X is oxygen.

30 5. The compound represented by the formula of claim 1 wherein R_1 is ethyl, R_2 is alkyl containing 1 to 6 carbon atoms and X is oxygen.

35 6. The compound represented by the formula of claim 1 wherein R_1 is alkyl containing 1 to 6 carbon atoms, R_2 is methyl and X is sulfur.

7. The compound represented by the formula of claim 1 wherein R_1 is alkyl containing 1 to 6 carbon atoms, R_2 is R_4-X-R_3 , R_3 is ethylene, R_4 is alkyl containing 1 to 4 carbon atoms and X is oxygen.

40 8. The amide of α -methoxy-n-propylpenicillin.

9. The amide of α -n-amyloxyethylpenicillin.

45 10. The amide of α -ethoxy-n-propylpenicillin.

11. The amide of α -(methoxyethoxy)-n-propylpenicillin.

12. The amide of α -methylmercapto-n-propylpenicillin.

13. The amide of α -methoxy- β -methylpropylpenicillin.

45 14. The amide of α -isobutoxethylpenicillin.
